CLOSURE OPERATOR CONTROL SYSTEM

Harold F. Collins, Rockford, Ill., assignor to
 Barber-Colman Company, Rockford, Ill., a corporation of Illinois

Application January 18, 1939, Serial No. 251,526

5 Claims. (Cl. 172—239)

The invention relates to closure operator control systems such as may be used with power actuated operators for doors, gates, and the like. It finds particular, although not exclusive, utility as applied to entrance doors for public garages and similar buildings.

Generally stated, the aim of the present invention is to provide a control system for power actuated closure operators which combines the features of minimum attention and manipulation by an attendant with maximum safety for persons or vehicles passing through the doorway or the like which is controlled by the closure.

More specifically stated, it is an object of the invention to provide, in combination with a power actuated closure operator, a control system embodying a control member which requires a sustained manual actuation by the attendant during the entire period of the closing movement of the closure member and which is adapted upon an interruption in the actuation of such control member during this closing movement to restore the closure automatically to open position. By this means the attendant is first of all compelled to give his attention to the closure while it is closing and during which time there is greatest danger of injury to a person or vehicle attempting to pass through the doorway or the like. Secondly, if an emergency arises during the closing operation, the attendant has only to release the manual control member in order for the door to return automatically to its safe open position.

Another object of the invention is to provide an apparatus of the character described embodying a novel and simplified electric control circuit arranged to be governed by a simple manually actuated switch mechanism.

Further objects and advantages of the invention will become apparent as the following description proceeds, taken in connection with the accompanying drawing in which

Figure 1 is a side elevation of a door and operating mechanism therefor as well as a control mechanism embodying the invention, the associated building structure being shown in vertical section.

Fig. 2 is a schematic wiring diagram of the apparatus of Fig. 1.

For purposes of illustration and explanation of its various novel features, the invention has been exemplified herein as embodied in an operating system for a large door or closure 10 such as may be used, for example, in a public garage.

The present invention is applicable to door operator systems generally irrespective of the particulars of construction of either the door itself or the drive mechanism for moving it many forms of which are well known in the art, and, accordingly, a brief description of these parts which are combined with the novel control system will suffice.

The particular door illustrated herein (Fig. 1) 10 is of the so-called overhead type. It is made up of a plurality of horizontal sections 11 hingedly connected so that the door may be slid upwardly and inwardly along a curved trackway 12 on which it is supported by rollers 13. When in its closed position, as shown, the door 10 is vertical and closes a doorway 14 in a wall 15. When moved upwardly along the trackway 12, it finally reaches an open position in which it rests on the horizontal upper arms of the trackway.

20 The power drive mechanism for the door 10 shown herein embodies a reversible electric motor 16 provided with alternatively energizable field windings 17^a and 17^b, one or the other of which is energized to accomplish rotation of the motor in the corresponding direction. Through appropriate speed reducing mechanism, the motor drives one of the sprockets 18 over which an endless roller chain 19 is led. To connect the chain 19 with the door 10, a carriage 20 is mounted for traversing movement along a horizontal trackway 21 located between the upper and lower reaches of the chain 19. A curved arm 22 is pivotally connected at its opposite ends to the carriage 20 and to a bracket 23 bolted to the inner upper portion of the inner face of the door 10. The carriage 20 is fixed to the chain 19 and accordingly, when the lower reach of the chain is moved to the left (as viewed in Fig. 1),

35 the door 10 is pulled upwardly and to the rear into its open position. Similarly, when the lower reach of the chain 19 is moved to the right or in the opposite direction, the door 10 is slid downwardly in its closed position. The configuration of the arm 22 and location of its pivots is such that, when in the position of Fig. 1, it prevents the door 10 from being pushed up, thus locking it closed.

40 The control system for the door operator motor 16 includes a control station designated generally by the numeral 24 (Fig. 2) and which may be located at any suitable point either near to or comparatively remote from the door 10 as may be desired in a particular installation. Preferably, the control station embodies two springs

urged push buttons 25 and 26 which are actuated respectively for opening and closing of the door 10. During the opening operation, the door 10 is moved to its position of greatest safety and, accordingly, there is little or no likelihood of an emergency that would require its reversal during its opening. For that reason, the circuits are preferably arranged so that once the door opening movement has been initiated, by a more or less momentary actuation of the "open" push button 25, it will continue for complete opening of the door even though this push button is subsequently released. Consequently, the attendant need only push the button 25 momentarily.

The closing movement of the door is comparatively dangerous, however, since someone is likely to try unexpectedly to enter the doorway at just about the time the door 10 is starting to descend. Consequently, it is desirable that the operator be compelled to give his attention to the operation of the system during the entire closing movement of the door. To this end, the push button 26 is arranged to actuate a switch of the hold-down type. In other words, the operator must manually hold the push button 26 in its depressed position during the entire closing movement of the door 10. Furthermore, the arrangement is such that if the operator releases the push button 26 at any time before the closing movement of the door is complete, the direction of door movement will be substantially instantaneous and automatically reversed so that the door is returned to its safe full open position.

The control station 24 in the particular construction herein shown (Fig. 2) includes a pair of normally open switch contacts 27 arranged to be bridged by depression of the "open" push button 25. Similarly, the "close" push button 26 is arranged, when depressed, to bridge a pair of normally open switch contacts 28 and to open a pair of normally closed contacts 29.

The second principal unit of the control apparatus shown is a limit switch assembly 30 (Fig. 1) mounted adjacent the chain 19. This assembly includes (Fig. 2) three sets of switch contacts 31, 32, and 33, each of which is normally urged to its open position by a suitable spring arrangement (not shown). The first pair of contacts 31 is arranged to be closed by an actuator finger 34 loosely journaled on a horizontal rockshaft 35. Integral with the actuator finger 34 is a two-horned cam lug 36 disposed in the horizontal path of movement of a lug or projection 37 fixed to the chain 19. When the parts are in the position shown in Fig. 2, movement of the lower reach of the chain 19 to the left will cause the lug 37 to strike the left hand horn of the cam 36 and swing it in a counter-clockwise direction so that the finger 34 releases the contacts 31, thereby permitting the latter to open. Such movement of the finger 34 in a counter-clockwise direction is limited by an integral stop finger 38 which contacts a fixed plate 39. Furthermore, an over-center spring-biased toggle mechanism serves to snap the actuator finger 34 to the one or the other of its extremities of movement toward which it is shifted. This toggle mechanism includes a pin 40 pivoted at its upper end to the actuator structure at a point eccentric with the rockshaft 35 and having its lower end projecting loosely through a hole 41 in the plate 39. A helical compression spring 42 encircles the pin 40 and bears at its opposite ends against the actuator plate and against the plate 39. It will thus be seen that, in the oscillation of the ac-

tuator finger 34, the toggle passes through its dead center position so that the spring 42 snaps the finger 34 to its fully open or fully closed position.

5 Fixed on the rockshaft 35 is an actuator for the contacts 32 which is substantially similar to that heretofore described for the contacts 31. This actuator includes a finger 43 fashioned as an integral projection on a plate pinned to the rockshaft 35. On this plate is formed a two horned cam 44 as well as a stop finger 45 co-operable with the fixed plate 39. The cam 44 is arranged to be engaged by a second projection 47 carried by the chain 19. As in the case of the first actuator described, the pin 48 and spring 49 serve to complete a toggle mechanism for the actuator to accomplish a snap acting type of movement for it. With the parts disposed as shown in Fig. 2, the projection 47 strikes the left hand horn of the cam 44 when the lower reach of the chain 19 moves to the left, thereby swinging the actuator finger 43 downwardly to close the contacts 32.

The third set of contacts 33 in the limit switch assembly 30 are actuated in coincidence with the second set of contacts 32 by an actuator finger 50 which is also pinned to the rockshaft 35. Since the actuator cam 44 is fixed to the rockshaft 35, movement of this latter shaft, upon actuation of the cam 44 by the lug 47, serves to shift both of the actuator fingers 43 and 50 simultaneously. It will be noted, however, that the actuator finger 38 first described above moves independently of the rockshaft 35 since it is loosely journaled on it.

35 Current for the electric driving motor 16 and associated control system may be supplied from any suitable source such, for example, as alternating current supply lines L₁ and L₂. The system may, for example, be designed for operation from a conventional 110 volt alternating current supply line.

40 As a further safety measure, a brake 51 (Fig. 1) is applied to the motor 16, this brake being normally urged into braking position by a suitable spring mechanism (not shown). An electric solenoid 52 (Fig. 2) serves, when energized, to release the brake 51. Energization of the solenoid 52 is controlled by normally open contacts 53 of a relay 54 having an actuating winding 55 interposed in the common supply lead of the motor field windings 17^a-17^b. In this way the solenoid 52 is energized when, and only when, the motor 16 is in operation. Accordingly, inadvertent gravitational descent of the door 10 is effectively prevented at all times.

45 Having thus identified the principal elements of the apparatus, their interconnections will be pointed out in conjunction with the following description of the operation of the system. Assuming that the door 10 is closed as shown in Fig. 1, the control system parts will be in the positions illustrated in Fig. 2. To initiate opening of the door 10, the attendant need only depress the "open" push button 25 for a short interval. Closure of the switch contacts 27 by the push button 25 energizes one winding 17^b of the reversible motor 16 (through a circuit L₁-56-27-57-29-58-31-59-17^b-60-55-L₂). It will be noted that the actuating winding 55 of the solenoid controlling relay 54 is included in this circuit so that the contacts 53 are closed and the solenoid 52 thereby energized to release the brake 51. Also included in the circuit are the contacts 29 associated with the "close" push button 26 so that if the latter push button is inadvertently

depressed at the same time, it will not cause both motor field windings to be energized at once.

Upon initiation of the motor rotation for opening of the door 10 in the manner described, the lower reach of the chain 19 moves to the left (as viewed in Fig. 1), and after a very short movement in this direction, the projection 47 on the chain strikes the cam 44 oscillating it in a counter-clockwise direction to close the contacts 32 and 33. Such closure of the contacts 33 completes an energizing circuit for the motor field winding 17^b which is independent of the push button contacts 27 (L₁—61—33—62—29—58—31—59—17^b—60—55—L₂) so that the motor 16 continues to be energized for opening of the door 10 even though the push button 25 is thereafter released. This opening movement of the door continues until at the point of its completion, the projection 37 on the chain 19 strikes the cam 36 thereby shifting it to the left (as viewed in Fig. 2) to open the contacts 31. Opening of these latter contacts interrupts the energizing circuit for the motor 16 as well as for the solenoid relay 54 so that the motor is stopped and the brake 51 automatically applied when the door is fully open.

To close the door 10, the operator depresses the "close" push button 26 thereby energizing the alternative field winding 17^a of the motor 16 (through a circuit L₁—63—28—64—32—65—17^a—60—55—L₂). It will be noted that this energizing circuit also includes the actuating winding 55 of the solenoid controlling relay 54 so that the brake 51 is automatically released. During the initial closing movement of the door, the projection 37 on the chain 19 strikes the loose cam 36 and oscillates it in a clockwise direction (as viewed in Fig. 2) to reclose the contacts 31. It will be noted that such reclosure of the contacts 31 does not energize the other motor field winding 17^b, however, since the circuit for this latter winding is interrupted at the contacts 29 so long as the "close" push button 26 is held depressed. The operator holds the push button 26 depressed through the entire closing movement of the door 10. At the termination of this closing movement, the second projection 47 on the chain 19 finally strikes the cam 44 and returns the rockshaft 35 to its position shown in Fig. 2 so that the contacts 32 and 33 are opened. In this way, the energizing winding 17^a for the motor 16 is finally open circuited, as is the relay 54, so that the motor 16 is stopped and the brake 51 applied.

A release of the "close" push button 26 at any time during the closing movement of the door 10 causes the door to be automatically restored to its open position. Such release causes the contacts 28 to be opened so that the motor winding 17^a is open-circuited and at the same time, the contacts 29 are closed. Closure of these contacts completes a circuit for the other motor energizing winding 17^b since the contacts 31 are reclosed at the beginning of the closing movement of the door as was previously noted. In this way, the motor 16 is energized for opening movement of the door and returns the same to its fully open position. The motor 16 is, of course, stopped automatically at the completion of the opening movement in the manner previously described. In this way, the attendant is compelled to give his attention to the operation of the system during the closing of the door 10 since he must hold the "close" push button 26 depressed throughout the entire closing movement of the door. Furthermore, if an emergency arises such as an unexpected attempt of some person or vehicle to

enter the doorway 15, the attendant has only to release the push button 26 in order to cause the door 10 to reverse its movement and return to fully open position. It will thus be seen that during normal opening of the door, the operator has only to give a minimum amount of time and attention to the operation since he need only depress the "open" push button 25 more or less momentarily. During the comparatively dangerous closing of the door, however, maximum safety is achieved by compelling his attention to the operation and facilitating reopening of the door in case of necessity as described. Finally, the automatic reopening of the door, in the event the "close" push button 26 is released during the door closing operation, makes it impossible for the door to be left in a dangerous partially open position.

Although a particular embodiment of the invention has been shown and described in some detail, there is no intention to thereby limit the invention to such embodiment, but, on the other hand, the appended claims are intended to cover all modifications and alternative constructions falling within the spirit and scope of the invention.

I claim as my invention:

1. In a power operator for a closure member, the combination of a reversible electric motor driving means having two windings selectively energizable to cause opening and closing movement of said member, a circuit through said closing winding including a manually operable switch, a circuit for said opening winding including a switch which is closed and open when said manually operable switch is open and closed respectively and a second switch actuated in timed relation with movement of said member and held closed except when said member is in fully closed position, and an alternative circuit for said opening winding controlled by a second manually operable switch in parallel with said last mentioned switch.

2. The combination with a power actuated operating means for a member such as a door movable between first and second limit positions, and a pair of manually actuatable control members, of means responsive to a momentary actuation of one of said control members for causing said power actuating means to move said movable member from said first limit position to the second, means responsive only to a continuous actuation of the other of said control members for causing said power actuated means to move said member from said second limit position to the first, and means automatically rendered operative upon release of said other control member at any point in the last named movement of said movable member to cause said power actuated means to return the movable member to said second limit position.

3. In combination, a reversible electric driving motor adapted to be operatively connected to an associated movable member and having alternatively available first and second energizing circuits for operating the motor in corresponding directions of rotation for moving said member in respectively opposite directions between first and second limit positions, an electric supply circuit, individual connections between said supply circuit and said two energizing circuits, each of said connections having two pairs of normally open contacts interposed therein, means actuated in timed relation with the movement of said movable member for retaining one

of said pairs of contacts in each of said connections closed during movement of the member from said second to said first limit position or vice versa and for causing the pair of such contacts interposed in said first energizing circuit to open at the completion of the movement of said member to said second limit position to stop said motor and similarly for causing the pair of such contacts interposed in said second energizing circuit to open at the completion of the movement of said member to said first limit position to stop said motor, manually operable means for closing one or the other of the remaining pairs of contacts in each of said connections, means rendered operative upon an initiation of the movement of said member toward said first limit position for partially completing an additional connection between said supply circuit and said second energizing circuit, and means rendered operative upon opening of said manually actuated contacts in said connection to said first energizing circuit for finally completing said partially completed connection to said second energizing circuit to thereby cause the member to be returned toward its second limit position.

4. In combination, a reversible electric driving motor adapted to be operatively connected to an associated movable member and having alternatively available first and second energizing circuits for operating the motor in corresponding directions of rotation for moving said member in respectively opposite directions between first and second limit positions, means including a first switch for effecting a completion of said first energizing circuit to cause the motor to move said member toward said first limit position, means including second and third switches for effecting completion of said second energizing circuit to cause the motor to move said member toward said second limit position, means

- actuated in timed relation with the movement of said movable member for retaining said third switch closed during movement of the member from said first to said second limit position and for causing said third switch to open at the completion of the movement of said member to said first limit position to stop said motor, said first and second switches being normally open manually operable switches, alternatively available circuit means for effecting completion of said second energizing circuit, means rendered operative upon an initiation of the movement of a member toward said first limit position for preliminarily conditioning said alternative means for operation, and means rendered operative upon opening of said first switch for finally conditioning said preliminarily conditioned alternative means to complete said first energizing circuit and thereby cause the member to be returned toward its second limit position.
5. In a power operator for a closure member, the combination of a reversible electric motor driving means having two windings selectively energizable to cause opening and closing movement of said member, means including a manually operable switch for completing a circuit through said closing winding, means for completing a circuit for said opening winding, said last named means including a switch which is closed and opened when said manually operable switch is opened and closed respectively and a second switch actuated in timed relation with the movement of said member and held closed except when said member is in fully closed position, and an alternative means for completing an energizing circuit for said opening winding controlled by a second manually operable switch and connected in parallel with said last mentioned switch.
